UNITED STATES PATENT OFFICE.

ARTHUR LÉVY, OF PARIS, FRANCE.

FOLDING OPERA-GLASS.

1,024,730.

Specification of Letters Patent.

Patented Apr. 30, 1912.

Application filed June 8, 1911. Serial No. 631,960.

To all whom it may concern:

Be it known that I, ARTHUR LÉVY, optician, a citizen of the Republic of France, and residing at Paris, France, have invented 5 new and useful Improvements in Folding Opera-Glasses; and I do hereby declare the following to be a full, clear, and exact description of the same.

My present invention has for its object to 10 provide a folding double opera-glass which is characterized by the fact that when the opera-glass is non-folded the two tubular cases which may be made elliptical, oval, rectangular or the like in cross-section, are 15 located adjacently and parallel to each other, while when the opera-glass is folded said cases are alined one above the other.

My invention will be readily understood from the following description taken in connection with the accompanying drawings showing the construction of my invention and wherein:—

Figure 1 shows an elevation and vertical section of a non-folded opera-glass embodying my invention; Fig. 2 shows an elevation and partial section of the folded opera-glass, Fig. 3 shows the cross-section of a tubular case on line A—A of Fig. 1, and Fig. 4 is an enlarged sectional detail view of the 30 adjusting mechanism.

In the construction illustrated the arm 1 carries a portion of the ocular system together with the adjustable sections, while the tubes 2 are hinged at 3 to the sliding piece 4 movably arranged on the tubular shaft or pin 5. By merely turning the tubes 2 around the hinges 3 said tubes are brought in line with each other, the sliding piece 4 being then located in corresponding recesses 35 of the tubes 2. Said sliding piece 4 is movable from end to end on the tubular shaft or pin 5 and the arm 1 together with the eyeglasses and adjustable sections is brought into the tubes 2, 2. The adjustable sections 40 are housed within the tubes even when they are in their outermost position. Therefore said adjustable sections need not be moved inwardly before folding the opera-glass, so that after unfolding the latter the parts are 45 still in their previously adjusted position.

Referring to Fig. 4, *a* is the adjusting pin, *b* a thumb piece and *c* a tubular interiorly threaded member mounted in the tubular

shaft 5 and free to rotate therein. The adjusting screw *a* is threaded to correspond to 55 the interior threads of the member *c*, so that by turning the thumb piece *b*, the adjusting screw *a* may be forced in or out, as desired.

The rigidity of the arm 1 in its horizontal position is secured by links 6 pivoted at one 60 end 7 to the tubes and at the opposite end 8 to said arm 1.

The ends of the opera-glasses herein described may be closed by shutters 9, the form of which corresponds to the section of the 65 tubes, in order to completely close the tubular casing formed by the folded opera-glass. Each shutter 9 is connected by a hinge 10 to the respective tube 2. A rod 11 connected at one end with the link 6 and at the opposite 70 end with a lever 12 fulcrumed at 13 to the tube and connected by a rod 14 with the shutter causes the latter to be closed when the opera-glass is folded and to be opened for uncovering the glasses 16 when the opera-glass is unfolded. 75

In order to enable the rods 14 to extend outwardly the object-glasses 15 are mounted by means of peculiar metal fittings. The glasses 15 are first placed against a rib or 80 projections provided in the interior of the tubes, whereupon the fittings 17 are screwed down. The latter are formed of a ring 18 embracing the outer rim of the glass and an apertured metal disk, through the aperture 85 of which extends the rod 14.

Having thus fully described my invention, what I claim and desire to secure by Letters Patent is:—

1. A folding opera-glass, comprising in 90 combination two tubular cases, an intermediate adjusting pin, an eye-glass carrier, a member slidably arranged on said pin, hinges between the tubular cases and said slidably member, links pivotally connected 95 to the eye-glass carrier and the inner walls of the tubular casings, and means for automatically closing and opening the ends of the folded opera-glass, substantially as set forth. 100

2. A folding opera-glass, comprising in combination two tubular cases, an intermediate adjusting pin, an eye-glass carrier, a member slidably arranged on said pin, hinges between the tubular cases and said 105 slidably member, links pivotally connected

to the eye-glass carrier and the inner walls
of the tubular casings, shutters, hinged to
the object ends of the tubular cases and suit-
able connections between said shutters and
5 the said links whereby the shutters are auto-
matically closed and opened, substantially
as set forth.

In testimony whereof, I have signed my
name to this specification in the presence of
two subscribing witnesses.

ARTHUR LÉVY.
